UNITED STATES PATENT OFFICE.

TOREBJORN CONRAD KORSMO, OF MADISON, WISCONSIN, ASSIGNOR TO MADISON-KIPP CORPORATION, OF MADISON, WISCONSIN, A CORPORATION OF WISCONSIN.

DIE-CASTING MACHINE.

Original application filed March 6, 1925, Serial No. 13,543. Divided and this application filed February 5, 1926, Serial No. 86,285, and in Great Britain October 28, 1925.

This invention relates to die casting machines and particularly to the mechanism in such machines for opening and closing the separable die parts incident to the charging of the die and the ejection of the casting therefrom.

In die casting machines employing separable dies, it is necessary to have certain mechanism for opening the die by separating the die parts to permit removal of the casting, and for then bringing the parts together again to receive another charge. After remaining closed for a period sufficient to permit the casting to "freeze", the die is again opened by its operating mechanism and the casting removed. In cases where the operation of the machine is automatic, so that it carries out one or more casting cycles, without the assistance of an attendant, it is necessary that the die operating mechanism perform the above mentioned operations in timed relation with the operation of the other parts of the machine, such for instance, as the die charging and the casting ejecting mechanisms.

Heretofore, in die casting machine practice, the various die operating mechanisms used cause the separating movement of the movable die part (or parts) to begin at a very low speed. During the interval the die is open the casting is ejected, after which, the operating mechanism causes the die to close, the ending of the closing movement of the movable die part (or parts) also being effected with the movable part traveling at a very low speed.

In present practice, particularly where cores or the like are used in the die, or where a portion of the die cavity is formed in a die part which remains stationary when the die is opened, there is need of an efficient mechanism which will cause the movable die part (or parts) to begin the opening movement suddenly and at a comparatively high speed. When such a mechanism is used, the cores, in the one case, are pulled from the casting much more easily and cleanly, and in the other, the jerk of the opening movement serves very effectively to break the casting loose from the stationary part of the die.

It is a purpose of the present invention to

provide a die operating mechanism of the character just described. It is further intended that the mechanism shall actuate the movable die part so as to slow up or decelerate the opening movement of the latter following the initial high-speed portion of this movement. After reaching its full-open position the movable die part is started on its closing movement by the operating mechanism. The closing movement begins comparatively slowly and is then accelerated. The comparatively slow movement of the die part at the ending of its opening and the beginning of its closing movements allows ample time for ejection of the casting, cleaning of the die cavity, lubrication of the die, placing inserts in the die, or any other operations which are necessary or desirable before the next casting is made.

A further purpose is the provision of a die operating mechanism which, in closing the die, will operate to move and hold the die parts so that they fit accurately and tightly together. This is accomplished by designing the operating mechanism so that it will close the movable die part against the stationary die part at a time when the movable part is traveling at a comparatively high speed. Thus the movable part is suddenly arrested by collision with the other part.

The invention further contemplates that the die operating mechanism shall effect a "dwell" of the die parts in the closed position to permit the casting to "freeze"; also, that the same mechanism shall serve, during the "dwell", to lock the die in closed position against any pressure which might tend to open it, such for instance, as pressure produced by gases within the die.

A further object is the provision of a machine which permits ready change of dies and the use of dies of different sizes with a minimum of trouble.

This application is a division of a prior application for a die casting machine filed by me on March 6, 1925, Serial Number 13,543.

The accompanying drawings disclose a practical embodiment of the invention, wherein,

Fig. 1 is a front elevation of the invention

showing the relative positions of the various parts when the die is in the full-open position and, in dotted lines, the position of the die operating mechanism at a certain point during the closing movement of the die;

Fig. 2, a similar view showing the relative positions of the parts when the die is in closed position and, in dotted lines, the positions of the die operating mechanism at certain points during its operation;

Fig. 3, a plan view with the parts in the full line position of Fig. 2; and

Fig. 4, a horizontal sectional view of a portion of the die operating mechanism.

The stationary part of a separable die is represented at 1 in the drawings and the movable part is shown at 2. Die parts 1 and 2, when they assume the closed position of Fig. 2, form the die cavity 3, as a result of the co-operation of the usual depressions provided in the abutting faces of the die parts.

Stationary die part 1 is removably attached to the face of a hot plate 4, which latter forms a part of the main frame work of the machine. The movable die part 2 is removably mounted by any suitable means on the opposing face of the carriage 5. This carriage is provided at its corners with a front pair of bearings, 6, 6 and a rear pair of bearings 7, 7 through which extend a front pair of guide rods 8, 8 and a rear pair of rods 9, 9, respectively. Guide rods 8 and 9 at their left ends are fixedly mounted in hot plate 4 and at their opposite ends are similarly mounted in the left hand wall of a gear housing 10. The latter forms a part of the main framework of the machine. From the description just given, it will be seen that die part 2 is mounted so that it is adapted for reciprocation towards and from the stationary die part 1.

Located beneath stationary die part 1 is a melting pot 11 in which is mounted a goose-neck or pressure-chamber 12 by means of which molten metal is transferred from the melting pot into the cavity 3 of the die when it is closed, as shown in Fig. 2. The mechanism for operating pressure-chamber 12 is not shown, since this forms no part of the present invention, but is covered by my previously filed application hereinbefore referred to.

Mounted for movement on the lower part of hot plate 4 is a perforated plate 13 with which the nozzle of pressure-chamber 12 co-operates in charging the die. This also forms a part of the subject matter of my other application just mentioned.

Provided on the front and rear edges of hot plate 4 are split bearings 14, 15, respectively. Similar bearings 16, 17 are provided on the front and rear edges, respectively, of the left hand end wall of gear housing 10. Mounted for horizontal reciprocatory movement in bearings 14 and 16 is a rod 18.

A similar rod 19 is mounted in a like manner in bearings 15 and 17. Die carriage 5 is provided on its front and rear edges with split bearings 20, 21, respectively, through which extend freely rods 18 and 19.

Inasmuch as the machine, as will appear from Fig. 3, is symmetrical, that is, the parts in the front of the longitudinal axis thereof are duplicated at the rear of the axis, only the front part of the machine will be described in detail.

Rod 18 is threaded for a portion of its length on each side of bearing 20 on die carriage 5. A pair of nuts 22 is mounted on rod 18 to the left of carriage 5 and a second pair of nuts 23 is mounted on the rod to the right of carriage 5. On rod 18 between the carriage and the pair of nuts 23 is a coil spring 24 mounted thereon so as to be under compression at all times. Spring 24 and the corresponding spring at the rear of the machine serve, as will appear hereinafter, to hold die carriage 5 normally against the pair of nuts 22 and the corresponding pair of nuts at the rear of the machine.

To the right of the die is the front connecting rod 25 of the mechanism for opening and closing the die by reciprocating movable die part 2 on its guide rods. Removably mounted on rod 18 towards its right hand end by means of suitable nuts is a block 25'. Connecting rod 25 is pivotally connected in any suitable manner to block 25'. It will thus be seen that any horizontal reciprocating movement of the left hand end of connecting rod 25 will cause a corresponding reciprocatory movement to be imparted to movable die part 2 through the connections above described. The yieldable connection between rod 18 and carriage 5 allows the movable die part 2 to be brought into the closed position of Fig. 2 and then be held closed by yielding pressure, while rod 18 travels further to the left. The overtravel of rod 18 to the left after the die is closed permits the use of die parts of different thicknesses and simplifies adjustment of the parts. By adjusting the pairs of nuts 22, 23 and the corresponding pairs of nuts at the rear of the machine, proper pressure between die parts of any size may be secured. Fig.

3 shows clearly the manner in which spring 24 and the corresponding rear spring are compressed when the die is closed. This results in a relative movement between die carriage 5 and rods 18, 19, so that in the closed position of the die, die carriage 5 is spaced from the pairs of nuts 22, 22. However, when rods 18, 19 are again moved to the right by connecting rods 25, 25 to open the die, the pairs of nuts 22, 22 again engage die carriage 5 and carry it to the right on its guide rods as 18, 19 continue their movement in this direction. During the entire

time the die is open, springs 24, 24 serve to maintain die carriage 5 against the pairs of nuts 22, 22.

As hereinbefore stated, one of the objects 5 of this invention is to provide a driving mechanism for the movable die part 2 which will cause the latter to dwell in closed position for a suitable period to permit the charge of molten metal to freeze therein, 10 after which die part 2 is separated from the stationary part 1 with a jerk, that is, the movable die part begins its opening movement with the part moving at a relatively high speed. The opening movement of the 15 die part should then be decelerated gradually in order to allow ample time for such operations, for instance, as removal of the casting and lubrication of the die parts. The beginning of the closing movement 20 should also be comparatively slow, in order to lengthen the period in which the operations just mentioned may be performed. After this the closing movement of the die part 2 should be gradually accelerated so 25 that the ending of its closing movement will be relatively fast. The mechanism in the present machine for imparting the movements just mentioned to connecting rods 25, 25 and thence to movable die part 2 will now 30 be described.

Mounted in suitable bearings in gear housing 10, Fig. 3, is a rotatable shaft 26. Mounted centrally on shaft 26 is a worm wheel 27 adapted to be driven by any suitable means (not shown) so as to cause shaft 26 to revolve. Preferably these parts are operated so that shaft 26 revolves in a clockwise direction, as indicated in Figs. 1 and 2, and the following description is given with 40 this understanding.

The ends of shaft 26 project beyond their bearings in housing 10 and mounted rigidly thereon are parallel cranks 28, 28. The mechanism connecting the front crank 28 45 and front connecting rod 25 is the same as that connecting the corresponding parts at the rear of the machine. Therefore, only the front mechanism will be described.

On the outer end of crank 28 there is 50 provided a cam disk 29. Cam 29 is so formed that the major portion 30 of its periphery constitutes an arc of a circle. In the center of this circle on cam 29 there is suitably mounted a stud 31 which projects rigidly from the outer face of the cam. A very 55 satisfactory manner of mounting stud 31 on cam 29 is shown in Fig. 4. With this arrangement, stud 31 is provided with a reduced shank which extends through an opening provided for this purpose in cam 29. The end of the shank of stud 31 is threaded, whereby the stud may be secured in place by means of a nut 32. Mounted for rotation 60 on stud 31 is a ring-shaped roller 33. As clearly shown in the drawings, stud 31

and its roller 33 are disposed for free movement in a slot 34 provided in the right-hand end of connecting rod 25.

The outer end of stud 31 is threaded to receive a nut 35 having an enlarged base 70 portion 36 to retain connecting rod 25 on the stud.

Cam 29 is symmetrical with respect to the center line of crank 28 on which it is mounted. The peripheral portion 30 of the 75 cam constitutes the active or camming surface, as will appear hereinafter, while the remainder of the periphery, i. e., the peripheral portion 37, forms the dwell surface of the cam.

Mounted in a suitable opening in connecting rod 25 a short distance inward of slot 34, as shown in Fig. 4, is a second stud 38. This stud is also provided with a reduced threaded shank whereby it is rigidly mounted 85 on connecting rod 25 by means of nut 39. The outer end of stud 38 has an annular enlargement 40 formed thereon for the purpose of retaining a ring-shaped roller 41 on the stud.

Operation:—It will be assumed that the parts of the machine are in the positions which they occupy at the middle of the dwell or closed position of the die. This is shown in full lines in Fig. 2. It will be noted that 90 the various parts of the driving mechanism for the movable die part are so arranged and proportioned that, at this time, the centers of shaft 26, stud 31, stud 38 and the pivotal connection between connecting rod 25 100 and block 25' are in horizontal alignment with each other. Stud roller 41 is also in contact with the middle of the dwell 37 of cam 29. The parts thus being on dead center, the die parts are locked in closed position at this time against any pressure tending to force the die parts apart. As will appear hereinafter, the driving mechanism for movable die part 2 serves during the 105 entire dwell period to lock the die parts together against any such pressure as that just mentioned.

The parts of the die separating mechanism are arranged and proportioned so that, so long as stud roller 41 and the arc shaped 115 portion 30 of cam 29 are in contact stud roller 33 is confined in the outer or right-hand end of slot 34 in the connecting rod 25. This is clearly shown in Fig. 1. The dwell portion 37 of cam 29 is shaped so that 120 during continuous rotation of crank 28 no motion is imparted to movable die part 2 while the roller is in contact with the dwell portion. In other words, dwell portion 37 of cam 29 is shaped so that, as cam 29 moves 125 during the dwell period, stud roller 41 merely rides freely thereon so as to permit the right-hand end of connecting rod 25 to swing into its various positions incidental to the dwell of the die.

As crank 28 continues its rotary movement in a clockwise direction from the full line position of Fig. 2, stud roller 41 rides freely on the dwell 37 of cam 29 and stud 5 roller 33 moves towards the outer end of the slot 34 in connecting rod 25. Because of the pin-and-slot connection between crank 28 and connecting rod 25, no movement is imparted to movable die part 2 until stud 10 roller 33 reaches the righthand end of slot 34 and stud roller 41 passes from dwell 37 onto the arcuate portion 30 of cam 29. Until this occurs, and in fact throughout the entire dwell period, movable die part 2 15 is locked in closed position by its operating mechanism against any pressure tending to open the die.

Immediately upon the arrival of stud roller 33 in the outer end of slot 34 and the 20 movement of stud roller 41 onto cam surface 30, a common crank-and-connecting-rod connection is formed. At this point, crank 28 is in a substantially upright position, a 25 point at which the component of motion of the crank pin in the direction of motion of the die part is near its maximum, so that its further movement causes the movable die part to be moved to the right with a jerk, that is, to start suddenly and move at a relatively high speed. Upon the establishment 30 of crank-and-connecting-rod connection, the rate of movement of movable die part 2 gradually diminishes at an approximately harmonic rate until the die part reaches its 35 full open position, shown in full lines in Fig. 1.

In the full open position of the die, stud roller 33 is still in the outer end of slot 34 and remains in this position until stud roller 40 41 passes again into contact with dwell 37 of cam 29. Therefore, the closing movement of the die commences with approximately 45 harmonic accelerated motion. This acceleration continues until movable die part 2 arrives approximately at its closed position. At this time, the part is moving substantially at its maximum speed, or at least at a high speed as compared with its rate of movement in the interval between the beginning 50 of its opening movement and the ending of its closing movement. It is particularly desirable in the construction illustrated to have the die close with the movable part traveling at a high rate of speed. If the 55 movable die part were traveling comparatively slowly as it closes against the stationary die part, it would often fail to seat tightly. This might be occasioned by binding of die carriage 5 on its guide rods 8, 9, 60 or by the resistance offered by cores or the like located in the cavity 3 of the die. Closing the die with the movable part 2 traveling at a high speed causes the parts to engage tightly and accurately.

As soon as stud roller 41 passes from cam 65 surface 30 of cam 29 and onto dwell 37 of the cam, as indicated in dotted lines at the bottom of Fig. 2, the dwell period begins again and, as explained above, continued rotation of crank 28 does not effect any further movement of movable die part 2. Stud 70 roller 41 again rides freely on dwell 37 of the cam, while stud roller 33 moves inwardly in slot 34 of connecting rod 25, until the parts again assume the full line position of 75 Fig. 2.

The size of cam 29 and the exact shape of its periphery depend, of course, upon the movement which it is desired to impart to rod 18 through the connecting rod 25. 80

Although a practical embodiment of the invention has been illustrated and described, it is not intended to restrict the invention thereto except as it may be limited by the appended claims. 85

What is claimed is:—

1. In a die casting machine, the combination of a pair of co-operating die parts adapted to form a mold, means for moving one of said die parts towards and from the other for closing and opening the mold, and means for causing said movable die part to dwell in its closed position and to begin its opening movement and end its closing movement abruptly with sudden transition to or from approximately its maximum speed of motion. 90

2. In a die casting machine, the combination of a pair of co-operating die parts adapted to be brought together for forming 100 a casting and opened for removing the casting, and means for closing and opening the die, so that the ending of the closing movement and the beginning of the opening movement thereof occur abruptly with sudden transition from or to approximately its maximum speed of motion. 105

3. The combination in a die casting machine of a pair of co-operating die parts adapted to form a mold, means for moving 110 one of said die parts towards and from the other to close and open the mold, and means for causing the opening movement of the mold to begin suddenly and at relatively high speed and then gradually decelerate to 115 rest.

4. In a die casting machine, the combination of a die part mounted for reciprocation from an open to a closed position and vice versa; power operated means for reciprocating said die part; and means for causing the opening movement of said die part to begin suddenly and at high speed and gradually decelerate as it approaches its full-open position, said means also serving to cause a 120 dwell of said reciprocable die part in its closed position. 125

5. The combination in a die casting ma-

chine of a multi-part die, one of said parts being movable to open and close the die; means for supporting and guiding the movable die part; means for driving the movable die part, said driving means serving to operate the movable die part so that its closing movement continues without substantial deceleration as it approaches its limit and then abruptly terminates; and a yieldable connection between the movable die part and its driving means.

In testimony whereof I have signed my name to this specification.

TORBJORN CONRAD KORSMO.
